UNITED STATES PATENT OFFICE.

LOUIS V. ARONSON, OF NEWARK, NEW JERSEY, ASSIGNOR TO VOICES INCORPORATED,
A CORPORATION OF DELAWARE.

VOICE MECHANISM.

Application filed May 28, 1924. Serial No. 716,344.

My invention relates to improvements in voice mechanisms and more particularly to devices adapted to be inserted in dolls or toys whereby sounds may be issued therefrom in simulation of the words "pa-pa", "ma-ma", etc. The main object of the invention is to provide an arrangement which is not only self-contained but is simple and efficient in operation and inexpensive in construction. Further and more specific objects, features and advantages will more clearly appear from the detail description given below taken in connection with the accompanying sheet of drawings which forms a part of this specification.

In the drawings Fig. 1 is a vertical section taken through an apparatus embodying my improvements in one form and showing the bellows in the collapsed position. Fig. 2 is a similar view showing the bellows in a distended position. Fig. 3 is a transverse section taken on the line 3-3 of Fig. 1. Fig. 4 is a vertical section taken on the line 4-4 of Fig. 3.

Referring to the drawings 5 represents a cylindrical cardboard casing provided with a perforated metal cover or cap 6 clamped over the upper edge of the casing 5. Secured to the bottom of the casing 5 as shown in Figs. 1 and 2 and 4 is the lower end of a tubular bellows member 7, the same being made of suitable air-tight flexible material such as rubberized cloth. By "tubular" bellows I do not limit myself to a cylindrical bellows or a bellows which is circular in transverse cross-section, but include bellows of any cross-sectional shape. The lower end of the bellows member 7 is wrapped about the lower edge of the cylindrical casing 5 and is held secured to the lower end of the casing 5 by a heavy cardboard disk 9 inserted therein which disk 9 also closes the lower end of the bellows member 7 and casing 5. Extending up through the disk 9 is a flat metal post 10, the lower end of which is bent laterally as at 11 and lies within a cutaway portion on the lower side of the disk 9. A thin pasteboard disk 12 is pasted over the bottom of the disk 9 and extension 11 and over this is placed a pasteboard or metal cap 13 having its edges flanged as at 14 to extend a short distance up on the outside of the cylindrical casing 5. Arranged to slide back and forth on the

metal post guide 10 is a lead of weighty 55 member 15 having a centrally disposed slot therethrough to accommodate the member 10. The member 15 is provided with a chamber 16 on its underneath side at one side of the post 10 and the lower side of said 60 chamber 16 is covered by a metal cap 17 through which extends a reed pipe 18 carrying a suitable sound reed. On its top face the member 15 is provided with a cavity 19 open at the top. The side of the chamber 65 16 adjacent to the post is provided with a sound emission opening 20, and on the other side of the post 10 directly opposite the opening 20 the member 15 is cutaway as 70 at 21. A bleed hole is provided through the member 15 at 22 and another bleed hole is provided through the top of the chamber 16 at 23. The member 15 is provided with a depending laterally extending circular peripheral flange 23 and the upper end of the 75 tubular bellows member is secured to this flange by a clamping ring 24. A disk 25 is secured to the underneath side of the member 15. The disk 25 is centrally apertured to tightly fit over the lug 33 projecting downwardly from and integral with the member 15, with the post 10 extending therethrough. The disk 25 is provided with an aperture therethrough at 26 to permit air to escape from the bellows into the 80 space between the disk 25 and the bottom of member 15 and to the reed pipe 18 whereby when the bellows is compressed, air will escape through the reed pipe 18 and cause the 85 reed to be sounded, the air passing through 90 the reed pipe and the sound therefrom escaping from the chamber 16 through the opening 20 and through spaced openings 28 and 29 in the post 10 (when these openings register respectively with the opening 20) and 95 into the cavity 19 and thence out of the device through the perforated cap 6. The post 10 is provided with a projection 30 extending through an aperture in the cap 6 in order to better hold the post in suitable position.

In operation, assuming the parts to be in position shown in Fig. 2, the weighted head 15 will drop by gravity sliding down along the post 10 and being guided thereby, and air will be expelled from the bellows, at first largely through the bleed openings, but this escape of air will not cause the reed to

be sounded. When, however, the opening 20 registers with the opening 28 a rush of air will take place through the reed pipe 18 and out through the openings 20 and 28 causing the reed to speak and utter a sound like "ma". When the opening 20 just passes the opening 28 the member 10 will substantially close the opening 20 and thus interrupt the sound until the opening 20 registers 10 with the opening 29 which is longer thereby causing the reed to utter a longer sound "ma", thus producing a voice sound simulating "ma-ma", until the weighted head reaches substantially the position shown in 15 Figs. 1 and 4. The device may then be turned upside down or so that the weight 15 will by gravity slide back along the post 10 to its original position when upon again turning the device to substantially the up- 20 right position shown in Figs. 1 and 2, the operation will be repeated. It will be noted that the cavity 19 forms a wall within the casing which moves with the sound opening 20 and so bears a constant definite relation to 25 said opening at all times.

While I have described my improvements in great detail and with respect to a preferred embodiment thereof, I do not desire to be limited to such form or detail since 30 many changes and modifications may be made and the invention embodied in widely different forms without departing from the spirit and scope thereof in its broader aspects. I desire to cover all forms and 35 modifications coming within the language or scope of any one or more of the appended claims.

What I claim as new and desire to secure by Letters Patent is:

- 40 1. An arrangement of the class described having in combination a tubular bellows member, a head closing one end of said bellows member, a flat post secured to said head and extending through the bellows member, a weighty head for the other end of the bellows member, said weighty head being mounted to slide upon said post which passes therethrough, said weighty head having a sound chamber, a reed pipe carried by 50 said weighty head and adapted to issue sound into the sound chamber upon operation of the bellows, said post having a plurality of apertures therethrough and said sound chamber having a sound opening co- 55 operating therewith to cause the reed pipe to speak as the weighty head slides by gravity along the post.

2. An arrangement of the class described 60 having in combination, a tubular bellows member, a weighty head closing one end thereof, a head closing the other end thereof, a flat post secured with respect to the last mentioned head and extending through the bellows member and the weighty head, the weighty head having a sound chamber

on one side of the post and, connected with the interior of the bellows member through a reed pipe, and a cavity on the other side of the post open to the outside atmosphere, said sound chamber and post being provided with openings for the escape of sound from the sound chamber into said cavity and to the outside atmosphere. 70

3. An arrangement of the class described having in combination, a tubular bellows member, a weighty head closing one end thereof, a head closing the other end thereof, a flat post secured with respect to the last mentioned head and extending through the bellows member and the weighty head, 75 the weighty head having a sound chamber on one side of the post and, connected with the interior of the bellows member through a reed pipe, and a cavity on the other side of the post open to the outside atmosphere, 80 said sound chamber and post being provided with openings for the escape of sound from the sound chamber into said cavity and to the outside atmosphere, said weighty head also having a bleed opening therethrough 85 communicating with the interior of the bellows member independently of said reed pipe. 90

4. A sound producing device comprising 95 a casing, a tubular bellows member in the casing a head for one end of the bellows member and fixed with respect to the casing, a relatively movable head for the other end of the bellows member, said movable head being weighty whereby it will move back 100 and forth in the casing by gravity to compress and distend the bellows, said weighty head carrying a sound chamber, and a reed pipe adapted to emit sound into the sound chamber upon operation of the bellows, said sound chamber having a side opening for the issuance of sound therefrom and a flat valve member having cut away parts adapted to register with the said side opening during the operation of the bellows. 110

5. A sound producing device comprising 115 a post, a weight supported by and mounted upon the post freely slidably therealong, a sound producing element carried by the weight extending longitudinally in a direction transverse to the length of the post, and means whereby sliding movement of the weight along the post will produce interrupted sound of the sound producing element. 120

6. A sound producing device comprising 125 a protecting casing, a post arranged axially within the casing supported by having its opposite ends engaging the end walls of the casing, a weight supported by and mounted upon said post freely slidably therealong within and relative to the casing a sound producing element carried by the weight extending longitudinally in a direction trans- 130

whereby sliding movement of the weight along the post will produce interrupted sounding of said sound producing element.

7. A sound producing device comprising a casing, a tubular bellows member in the casing, a head for one end of the bellows member and fixed with respect to the casing, a relatively movable head for the other end of the bellows member, said movable head being weighty whereby it will move back and forth in the casing toward and from the fixed head by gravity to compress and distend the bellows, said weighty head also carrying a sound reed adapted to sound upon operation of the bellows, and a flat valve member secured with respect to said fixed head, said valve member having parts cut away through which the sound from the reed pipe is adapted to successively issue when the bellows is operated.

8. A sound producing device having in combination a tubular bellows, a relatively fixed head for one end of the bellows, a relatively movable head for the other end of the bellows, said movable head being weighty whereby it will move back and forth toward and from the fixed head by gravity to compress and distend the bellows, said weighty head having a hollow part in the weighty part of the head, and forming a sound chamber, a reed pipe operated by the bellows and issuing its sound into said sound chamber, said sound chamber having a sound exit opening and valve means for opening and closing said opening responsive to the operation of the bellows.

9. A sound producing device having in combination a tubular bellows, a relatively fixed head for one end of the bellows, a relatively movable head for the other end of the bellows, said movable head being weighty whereby it will move back and forth toward and from the fixed head by gravity to compress and distend the bellows, said weighty head having a hollow part in the weighty part of the head, and forming a sound chamber, a reed pipe operated by the bellows and issuing its sound into said sound chamber, said sound chamber having a sound exit opening and a flat valve member secured with respect to the fixed head, said valve member having cut away portions adapted to successively register with said exit opening to control the sound issuing therefrom responsive to the operation of the bellows.

10. A sound device having in combination a tubular bellows with two heads, one of said heads being relatively fixed and the other relatively movable and having a metallic weight whereby it will compress and distend the bellows by gravity, said metal weight having a hollow part forming a sound chamber, a reed carried by the weight and operated by the bellows and emitting

its sound into the sound chamber, said sound chamber having a sound emitting opening, and a valve member secured with respect to said fixed head and having an opening adapted to register with said sound emitting opening to control the sound therefrom responsive to the operation of the bellows.

11. The combination of a bellows, a head closing one end of said bellows, a flat post secured with respect to said head and extending through the bellows, a weighty head for the other end of the bellows, said weighty head being mounted to slide on said post which passes through the head, said weighty head having a sound chamber, a reed pipe carried by said weighty head and adapted to issue sound into the sound chamber upon operation of the bellows, said post having a cut away portion and said sound chamber having a sound opening cooperating therewith to cause the reed pipe to speak as the weighty head slides by gravity along the post.

12. The combination of a bellows, a weighty head for one end thereof, a head for the other end thereof, a post secured with respect to one of said heads, and extending through the bellows member, and other head, the said other head having a sound chamber on one side of the post, a reed adapted to issue sound into the sound chamber upon operation of the bellows, and a cavity in said sound chamber head on the other side of the post from the sound chamber, and open to the outside atmosphere, said sound chamber and post being provided with cooperating openings for the escape of sound from the sound chamber into said cavity.

13. The combination of a casing, a tubular bellows in said casing, said bellows having one head fixed with respect to the casing, a weighty head for the other end of the bellows and slideable back and forth in the casing to compress and distend the bellows by gravity, said weighty head having a sound chamber, a reed adapted to issue sound into said sound chamber upon operation of the bellows, and a flat post valve member fixed with respect to said first mentioned bellows head and provided with a cut away portion for controlling the issuance of sound from the sound chamber.

14. The combination of a casing, a tubular bellows in said casing, said bellows having one head fixed with respect to the casing, a weighty head for the other end of the bellows and slideable back and forth in the casing to compress and distend the bellows by gravity, said weighty head carrying a sound chamber, a reed carried by said weighty head and adapted to issue sound into said sound chamber upon operation of the bellows, and a valve member

fixed with respect to said first mentioned bellows head and provided with an opening extending therethrough for controlling the issuance of sound from the sound chamber.

5 15. The combination of a casing, a tubular bellows in said casing, said bellows having one head fixed with respect to the casing, a weighty head for the other end of the bellows and slidable back and forth in the casing to compress and distend the bellows by gravity, said weighty head carrying a sound chamber, a reed carried by said weighty head and adapted to issue sound into said sound chamber upon operation of the bellows, and a valve member fixed with respect to said first mentioned bellows head and provided with an opening extending therethrough for controlling the issuance of sound from the sound chamber, said valve member extending through said weighty head and said weighty head being adapted to slide on said valve member.

16. A sound producing device comprising 25 a casing, a tubular bellows in the casing, said bellows having one head fixed with respect to the casing and another head being a weighty head movable back and forth in the casing to compress and distend the bellows by gravity, one of said heads carrying a sound chamber, a reed pipe adapted to emit sound into the sound chamber upon operation of the bellows, said sound chamber having a side opening for the issuance 35 of sound therefrom and a flat valve member fixed with respect to the other head, said flat valve member having a cut away part adapted to register with said side opening during the operation of the bellows.

40 17. A sound producing device comprising a casing, a tubular bellows in the casing, said bellows having one head fixed with respect to the casing and another head being a weighty head movable back and forth in the casing to compress and distend the bellows by gravity, one of said heads carrying a sound chamber, a reed pipe adapted to emit sound into the sound chamber upon operation of the bellows, said sound chamber having a side opening for the issuance 45 of sound therefrom and a valve member fixed with respect to the other head, said valve member having an opening extending transversely therethrough adapted to register with said side opening during the operation 50 of the bellows.

18. A sound producing device comprising a casing, a tubular bellows in the casing, said bellows having one head fixed with respect to the casing and another head being a weighty head movable back and forth in the casing to compress and distend the bellows by gravity, one of said heads carrying a sound chamber, a reed pipe carried by said last mentioned head and adapted 60 to emit sound into the sound chamber upon operation of the bellows, said sound chamber having a side opening for the issuance of sound therefrom and a flat valve member fixed with respect to the other head, said flat valve member having a plurality of cut away parts adapted to register with said side opening during the operation of the bellows, and said flat valve member passing slidably through the head carrying the 75 sound chamber.

19. The combination of a casing, a tubular bellows therein having one head fixed with respect to the casing, the other head of the bellows being a weighty head movable 80 back and forth in the casing by gravity to compress and distend the bellows, a sound chamber carried with the weighty head, a sound reed carried with the weighty head and the sound from which issues into the 85 sound chamber, and said sound chamber having a sound emission opening, and a valve post secured with respect to the casing and cooperating to control said sound emission opening as the bellows is operated. 90

20. The combination of a casing, a tubular bellows therein having one head fixed with respect to the casing, the other head of the bellows being a weighty head movable 95 back and forth in the casing by gravity to compress and distend the bellows, a sound chamber carried with the weighty head, a sound reed carried with the weighty head and the sound from which issues into the sound chamber, and said sound chamber 100 having a sound emission opening, and a valve post secured with respect to the casing and cooperating to control said sound emission opening as the bellows is operated, said valve post extending through the bellows 105 and weighty head and acting as a guide for the latter in its movement back and forth in the casing.

In testimony whereof I have signed my name to this specification.

LOUIS V. ARONSON.
